UNITED STATES PATENT OFFICE.

THOMAS A. TAYLOR, OF KENTON, OHIO.

FUEL-HEATER.

1,109,025.

Specification of Letters Patent.

Patented Sept. 1, 1914.

Application filed September 8, 1913. Serial No. 788,734.

To all whom it may concern:

Be it known that I, THOMAS A. TAYLOR, a citizen of the United States, residing at Kenton, in the county of Hardin and State of Ohio, have invented certain new and useful Improvements in Fuel-Heaters, of which the following is a specification.

The present invention relates to an improved fuel heater to be used in connection with and attached to an internal combustion or vapor engine.

The primary object of the invention is the provision of means for heating kerosene and air as fuel for vapor explosive engines, and in order to accomplish this purpose economically and conveniently, I utilize the exhaust gases from the explosive engine as they pass through the heating device to bring the kerosene to almost the boiling point and also to heat the air to a very high temperature and these conditions provide a more efficient mixture for fuel than that obtained from gasolene. In connection with the attachment I utilize a gasolene carbureter for the initial combustion in the engine, and after the engine is running, and the exhaust therefrom has heated the kerosene so that it may be thoroughly volatilized, the gasolene is shut off and kerosene used exclusively. In the accompanying drawings I have illustrated one complete example of the physical embodiment of my invention constructed according to the best mode I have so far devised for the practical application of the principles of the invention.

Figure 1 is a vertical central sectional view through the heater and an accompanying carbureter, the latter being shown as connected to an engine, and the former connected with the exhaust from the engine. Fig. 2 is a sectional view of the carbureter on line 2—2 of Fig. 1. Fig. 3 is a transverse sectional view showing a portion of the fuel heater and illustrating particularly the kerosene coil with its ends leading to the fuel tank and to the carbureter.

In the preferred embodiment of my invention I employ the two heads 1 and 2 between which are fixed the outer shell 3 and the inner casing 4, both cylindrical in form and spaced apart to form a hot air chamber 5 which is open to the atmosphere through openings 6 in the lower end of the shell. The heads of the heating drum are perforated, the head 1 to receive a pipe 7 connected with the exhaust of the engine, and

the head 2 to receive a perforated tube 8 which extends up into the interior of the casing 4 and has a closed pointed end 9. Glands 10, 10 are used to pack the joints of the pipes 7 and 8 with the two heads, and these pipes are in alinement to receive and convey the hot gases of combustion from the working engine.

A coil of pipe 11 is located within the inner casing 4, adjacent its wall, one end of which, 12, is connected with a kerosene supply tank (not shown) and the other end 13 is connected to a kerosene tank 14 forming part of a carbureter to be described. Sleeves or hollow bosses 15, integral with the casing 4 are located in the space 5, through which the pipe ends pass, and lock nuts 16, 16, are employed to make a secure fastening of the pipes at the outside of the shell 3.

The carbureter illustrated in Fig. 2 is connected with the hot air space 5 through the opening in the shell and the short flanged pipe 17, and the carbureter is secured to the heater drum and engine by means of the flanges 18 and 19 and suitable bolts. The carbureter cylinder 20 is open to the passage of heated air from the heater drum to the engine, but the passage of the air is controlled and regulated by means of a turn plug or valve 21 located in the open lower end of the cylinder and revoluble therein. This valve is formed with an annular groove 22, and by means of the bolts 23 in the wall of the cylinder which enter the groove, the plug is held against displacement and may be turned by the handle 24. The valve is cylindrical in cross section and is cut away or cupped at 25 to provide communication between the short pipe 17 and the interior of the cylinder 20. It will be understood that by revolving the recessed plug the area of communication may be increased or decreased. The heated kerosene passes from the tank 14 through the tube 26 and the flow of sprayed liquid is controlled by the needle valve 27 which is threaded in the top or cover 28 of the cylinder, and an overflow pipe 29 is used to carry back to the fuel supply tank any excess of kerosene in the tank 14.

A second needle valve 30 controls the supply of gasolene in the cylinder 20, from the gasolene tank 31 which is equipped with the usual float 32 and valve 33 and receives a supply from the inlet pipe. By extending the tube or outlet pipe 8 with its perforations entirely through

the coils and far into the heating or exhaust chamber of the casing 4, the full heating properties of the gases of combustion as they are exhausted from the engine, are felt upon the heating coil as the gases flow through the heating chamber and into the perforations of the outlet pipe.

In operation, the gasoline carbureter is used to supply fuel in the usual way to the engine. After the engine has been running a sufficient time so that the exhaust gases of combustion which pass through the heater have raised the temperature of the kerosene in the coils to almost the boiling point, the valve 30 is closed, and the valve 27 which has been previously closed, is now opened, shutting off the gasoline supply and opening up the kerosene supply. The kerosene in the coils is heated by the gases as they pass through the casing 4 and the perforated pipe 8, and the air for fuel passing through the space 5 is heated also and passes through the plug valve 21 to the cylinder 20. The vaporized kerosene in its heated condition, and the heated air are commingled in the cylinder or carbureting chamber 20 and pass from there into the cylinders of the engine. By thus heating the kerosene, which normally is less volatile than gasoline, and heating the air, a mixture is produced which provides a more powerful explosion than is obtained from gasoline, a comparatively perfect combustion is attained, and the objectionable soot or smoke which is so injurious to the engine, spark plug, etc., is eliminated.

The attachment may be made to form a

part of an engine as originally constructed, and it is equally applicable for use with existing engines of various types by modifying the size of the attachment, and changing the design of the attaching flanges, etc.

Having thus fully described my invention, what I claim is:

1. In a fluid fuel heater the combination of a perforated shell forming an air chamber, an imperforate casing within the shell and a coil in the casing having inlet and outlet, an inlet pipe to the casing, and a perforated outlet pipe extending from one end of the casing to near the other end thereof, whereby the coil is heated by gases flowing through the casing to the outlet pipe.

2. In a fluid fuel heater, the combination with a carbureting chamber and kerosene tank communicating therewith, of a perforated shell, an imperforate casing within the shell, an inlet for heated gases to said casing and an outlet pipe, perforated, and extending from one end of the casing to near the other, the space between the shell and casing forming an air chamber and communicating with the carbureting chamber, and a coil in the casing communicating with said tank, whereby the coil is heated by the gases flowing through the casing to the outlet pipe.

In testimony whereof I affix my signature in presence of two witnesses.

THOMAS A. TAYLOR.
